UNITED STATES PATENT OFFICE.

FRANK G. BEETEM, OF PHILADELPHIA, PENNSYLVANIA.

RADIO RECEIVING APPARATUS.

Application filed June 16, 1920. Serial No. 389,442.

To all whom it may concern:

Be it known that I, FRANK G. BEETEM, a citizen of the United States, residing at Philadelphia, in the county of Philadelphia and State of Pennsylvania, have invented 5 certain new and useful Improvements in Radio Receiving Apparatus, of which the following is a specification.

This invention relates to radio receiving 10 systems embodying audions or vacuum tubes.

One of the objects of my invention is to provide a suitable regulating device for the filament circuit of an audion or vacuum 15 tube, so arranged with adjustable hand-operated resistances that any given setting for the filament excitation may be obtained and afterward the filament current and voltage will remain substantially constant, 20 irrespective of normal changes in the voltage of the battery or other source supplying this filament circuit.

It is a well known fact that the voltage of primary or secondary batteries varies 25 throughout the discharge of the battery. Starting at a given point the tendency is for the voltage to decrease more or less steadily with time during the period when current is being drawn from the battery. 30 With some forms or types of batteries this voltage regulation is very poor and so in the case of the filament circuit of audion or vacuum tubes, compensation for the decrease of voltage of the battery exciting the filament is made from time to time with adjustable resistances in series with the filament in the battery circuit, the amount of resistance included in the filament circuit being varied by manual adjustment to maintain 35 constant current.

In some types of radio receiving apparatus, and especially with batteries having poor voltage characteristics, the necessity for constant adjustment is exceedingly objectionable and frequently results in the loss of signals or portions thereof, which under the conditions of a constant filament current would not occur.

A particular object of my invention is to 40 render it possible to use any type of battery, at least for a considerable period, without the necessity for constant adjustment. To accomplish this, I propose to include in the filament circuit a device which will, 45 within the limits of its particular design,

automatically maintain a constant filament-current and consequently a constant filament temperature.

Further, the invention has for an object the provision of suitable means for simplifying the control of audions or vacuum tubes in the reception of oscillations of definite radio frequency by providing automatic means for maintaining constant current in the filament circuit of the audion in 60 combination with manual means for making the initial adjustment whereby the automatic means is operated at its point of maximum effectiveness and at the same time the current in the filament is adjusted to the desired value, and is thereafter maintained at 65 said value automatically and without further manual adjustment, notwithstanding variations in the voltage of the source of current.

Further features and objects of my invention will be more fully understood from the following detailed description and the accompanying drawing, in which:

Figure 1 is a diagrammatic view of the application of my invention to a form of radio receiving circuit.

Figure 2 is a diagram showing one relation or current and voltage of an iron wire ballast.

Referring to Fig. 1, the antenna 1, grounded at 2, is suitably connected to the closed, tuned circuit of the receiving apparatus as by means of the coil 3 inductively arranged with the reactance coil 4 of the closed tuned 90 circuit. The capacity of the antenna circuit is adjusted by the variable condenser 3^a. The condensance of the closed tuned circuit is provided by the variable condenser 5, connected by the leads 6, 7, with the respective 95 leads 8, 9, of the inductance coil 4.

One lead of the condenser 5, say the lead 6, is connected to the conductor 10, through the condenser 11 and to the grid 12 of the audion or vacuum tube 13, whereas the other 100 lead 7 of the condenser 5 is connected by the conductor 14 to one terminal 15 of the filament 16 of the audion or vacuum tube 13.

The plate or anode 17 is connected by the conductor 18 to one terminal of the head 105 telephone 19, or other suitable aural indicating device, the other terminal of such indicating device 19 being connected by the conductor 20 to one terminal of a battery 21, such as a storage battery, through such bat- 110

tery 21, thence through the conductor 22, conductor 23 and to the terminal 15 of the filament 16.

Between the said terminal 15 of the filament 16 of the audion or vacuum tube 13, and its other terminal 24, I arrange the means for maintaining the current value of the electric current supplied by the battery 25 to the filament 16 substantially constant, notwithstanding variations in electromotive force or potential of the battery 25.

As one form of such means I have shown, as indicated in Fig. 1, the iron wire ballast 26, one terminal 27 being connected by the lead 28 through the storage battery 25 to the lead 29, connected by the conductor 23 to the terminal 15 of the filament 16, the other terminal 30 of the iron wire ballast 26 being connected by the lead 31 through the variable ohmic resistance 32 and the conductor 33 to the terminal 24 of the filament 16.

In some forms of apparatus I may connect between the filament terminals 15 and 24, a variable ohmic resistance, 34, of zero or slightly negative temperature coefficient material, which may be used to divert a part of the current furnished by the battery 25, so that the whole current in lead 33 does not pass through the filament 16. Now for any adjustment of resistance 34 the filament current will remain practically constant at the adjusted value since the current in lead 33 is maintained substantially constant by the action of the ballast 26. Upon tuning the closed circuit the resistance 32 is adjusted so that the maximum normal drop of potential across the ballast 26, as indicated by the curve shown in Fig. 2, is obtained and at the same time resistance 34 is adjusted for the beat-tone indicated by the head telephone. Of course the system is workable without the resistances 32 or 34, for any particular set of conditions but the addition of these resistances simplifies the problem of iron wire ballast manufacture. The addition of the resistance 34 also improves the regulation of the filament current. A larger ballast is required when this resistance 34 is used.

Upon tuning the closed circuit including the inductance coil 4 and condenser 5 to the frequency desired to be received, the ohmic resistance 34 is adjusted for the beat-tone indicated by the head telephone as desired by the operator. Assuming that the electromotive force or potential of the battery 25 has any certain value at the instant of such adjustment as is indicated by the ordinate 40, on the coordinate axes of current and electromotive force values indicated in Fig. 2, the ensuing drop in potential of the battery takes place without substantially altering the current value. The current-electromotive force curve plotted to right-angled coordinate axes includes a curve portion 41 located between the point 42 and the point 43

which is substantially parallel to the abscissa axis, as indicated in Fig. 2; in other words, the current values represented by the ordinates 44, 45, at the extreme limits of such curved portion 41, are substantially equal, 70 and such curve portion 41 is substantially a straight line between such point 42 and such point 43.

By reason of my invention, upon obtaining the initial adjustment of the receiving apparatus, such initial adjustment need not be disturbed notwithstanding variations in potential of the source of electric energy energizing the filament of the audion or vacuum tube. 80

In order to more clearly explain the operation of the several elements of the combination described above, the following numerical examples are given:—

Assume the characteristics of the iron wire ballast are such that the coordinates of point 43 in Fig. 2 correspond to 2.00 amperes (ordinate) and 1.5 volts (abscissa) and the coordinates of point 42 correspond to 1.98 amperes (ordinate) and 1.0 volt (abscissa). 90 To secure the most effective automatic control, the iron wire ballast should be operated between these limits. Assume, further, that for some desired adjustment of the reception circuit the filament should carry 1.5 amperes and when carrying this current, the voltage across its terminals is 3.6 volts. Assume also that the initial voltage of the battery 25 is 6.0 volts, but that this may drop to 5.5 volts as it discharges. In order that the 100 iron wire ballast may carry 2.00 amperes, and the filament may at the same time carry 1.50 amperes, the resistance 34 should be adjusted to divert 0.5 ampere at 3.6 volts,—i. e., it should have a value of 7.2 ohms. Then 105 the sum of the voltage across the filament (3.6 volts) and the desired voltage across the iron wire ballast (1.5 volts) is 5.1 volts. Since the initial battery voltage is 6.0 volts, the difference between this and 5.1 volts (0.9 110 volts) must be absorbed by the resistance 32 when carrying the total current of 2.0 amperes. Therefore, resistance 32 must be adjusted to a value of 0.45 ohm. Now if the 115 battery voltage drops to 5.5 volts, the total current, by reason of the automatic action of the iron wire ballast, will not fall below 1.98 amperes, though the voltage across this ballast may drop from 1.5 volts to 1.0, thus compensating for the drop in battery 120 voltage, while maintaining the total current and therefore the current in the filament constant.

Now suppose for some other adjustment of the reception circuit it is desired to maintain only 1.0 ampere in the filament, at which current value the voltage across its terminal is say 3.0 volts. In order to maintain the maximum effectiveness of the iron wire ballast, the total current should still be 2.0 130

ampères. The adjustment of resistance 34 should therefore be such as to divert 1.0 ampere at 3.0 volts,—i. e., its value should be 3.0 ohms. The total drop across the filament (3.0 volts) and the iron wire ballast (initially 1.5 volts) will then be 4.5 volts, and the initial battery voltage being 6.0 volts, it is necessary to adjust the resistance 32 to give a drop of 1.5 when carrying 2.0 amperes, i. e., its value should be 0.75 ohms. If now, the battery voltage drops from 6.0 volts to 5.5 volts, the voltage across the iron wire ballast will drop from 1.5 volts to 1.0 volts as before, while maintaining the current constant.

The above examples will clearly explain how with the combination disclosed the filament current may be manually adjusted at any desired value within the limits for which 20 the apparatus is designed and thereafter automatically maintained at said value throughout wide variations in the voltage of the source, and these results are obtained without any change in the design of the iron 25 wire ballast. In other words, the same iron wire ballast, though designed to maintain a constant current of 2.00 amperes may be used to control a current of either 1.5 or 1.0 or in fact any other current not exceeding 2.0 amperes in the filament.

Whereas I have described my invention by reference to specific forms thereof, it will be understood that many changes and modifications may be made without departing 35 from the spirit of the invention, as defined by the appended claims.

What I claim is:

1. In combination, the filament of an audion or vacuum tube, a source of current

therefor, a resistor of high positive temperature coefficient connected between the source and the filament and adapted to maintain a substantially constant current flow, and a resistor connected in parallel with the filament to divert a portion of said current whereby 45 the current in the filament is maintained constant at a different value from that of the current from the source.

2. In combination, the filament of an audion or vacuum tube, a source of current 50 therefor, an iron wire ballast connected between the source and the filament and adapted to maintain a substantially constant flow of current within a certain range of impressed voltage, a resistor connected in series with said ballast and adapted to adjust said impressed voltage within the desired range, and a resistor connected in parallel with the filament whereby the current in said filament is maintained substantially constant at a value different from that through the iron wire ballast.

3. In combination, the filament of an audion or vacuum tube, a source of current 55 therefor, an iron wire ballast connected between the source and the filament and adapted to maintain a substantially constant flow of current within a certain range of impressed voltage, an adjustable resistor connected in series with said ballast and 60 adapted to adjust said impressed voltage within the desired range and an adjustable resistor connected in parallel with the filament for adjusting the proportion of said constant current which flows through the filament.

In testimony whereof I affix my signature.
FRANK G. BEETEM.
